ROTARY INTAGLIO INK FOUNTAIN

Charles A. Harless, Riverside, Conn., assignor to
 R. Hoe & Co., Inc., New York, N. Y., a corpora-
 tion of New York

Application June 6, 1950, Serial No. 166,456

4 Claims. (Cl. 101—157)

1

This invention relates to improvements in rotary intaglio printing machines and, more particularly, in ink fountains for use in such machines.

In rotary intaglio ink fountains, and especially in such fountains where the cylinder is inked by running in a pool of ink within the fountain, there is a tendency for ink to find its way out around the cylinder shaft and to enter the bearings and the gearing. With many inks there is an abrasive action which will ultimately cause deterioration of the bearings and gearing. It is an object of the invention to provide improved means for preventing the emergence of ink around the cylinder shaft or journals.

In many cases a given fountain is utilized with printing cylinders of different diameters. The printing cylinder diameter will depend upon the size of the product to be printed and upon whether it is printed "one up" or whether the subject matter to be printed is repeated one or more times around the cylinder circumference. Generally speaking, and with a given size fountain, more ink leakage trouble will be experienced with small cylinders, and it is desirable in any event to provide suitable leakage protection for any of a range of sizes of cylinder.

It is an object of the invention to provide improved means for preventing the escape of ink around the cylinder shaft, which is adaptable to cylinders of different diameters.

With the foregoing object, and still other objects which will appear in mind, a fountain embodying the invention will now be described with reference to the accompanying drawing, and the features forming the invention will then be pointed out more particularly in the appended claims.

In the drawing:

Figure 1 is a cross section through the fountain, on the line 1—1 of Figure 2, and showing also certain related structures;

Figure 2 is a section of the line 2—2 of Figure 1, and showing one end of the fountain;

Figure 3 is a plan view of the end of the fountain shown in Figure 2, with certain parts removed;

Figure 4 is a section on the line 4—4 of Figure 2;

Figure 5 is an elevation view of a baffle element utilized with the fountain of previous figures;

Figure 6 is a section on the line 6—6 of Figure 5 and on an enlarged scale; and

Figure 7 is a section view similar to Figure 6, but showing the fountain without the baffle of

Figure 5, and illustrating operation with the largest cylinder.

The fountain comprises a casting or body 1 having end flange or bracket elements 2 by means of which the fountain is fastened to the press frames 4 so that the brackets 2 lie flat against the press frames. Machine screws or bolts 3 may be utilized for this purpose.

The printing cylinder 5 is carried in bearings 6 which seat in the press frames in the usual manner and are accommodated by the fountain, as indicated in Figures 2 and 3. Cover elements indicated at 6' in Figure 1, form a closure on the doctor side of the fountain and the reciprocating doctor 7 is maintained in position for removing excess ink from the printing cylinder. The printing cylinder applies the ink remaining in its etchings to the web of paper indicated at W, the web being pressed against the printing cylinder by an impression roller 8, as usual. The printing cylinder rotates counter-clockwise, as indicated in Figure 1. On the opposite side from the doctor is provided a hinged cover 9, coming close to the surface of the cylinder 5, and the ends of the cylinder 5 are covered over by means of arcuate covers 10. Suitable doctor mechanism and closure arrangements as well as suitable frame and ink circulating arrangements are well known in the art, being shown for example in the patents to Zuckerman No. 2,097,791 and Heller No. 2,292,344. Since such elements form in themselves, no part of the present invention, they are not described in detail.

The central part of the fountain forms well 11, for holding a body of ink to be applied to the cylinder. A series of inlet ports 12 runs along the side of the fountain opposite the doctor, and a depression 14 is provided centrally of the well 11 having an outlet port 15, as indicated. A series of overflow ports 13 runs along the side of the fountain under the doctor. The ink may be circulated through the fountain, entering by ports 12 and passing out through the port 15, the quantity of ink in the fountain being regulated by the rate of supply and any excess overflowing through the ports 13. The present invention is not concerned with the specific ink circulation adopted.

In a typical ink fountain intended for news-paper or similar printing, the web of paper printed on may be about six feet wide and the cylinder somewhat longer. It is undesirable to make the press or the distance between press frames any wider than necessary as this increases 55 the weight of the parts and the floor space re-

quired without any corresponding benefit. In a typical installation, the distance between the end of the printing cylinder and the press frame may be only five or six inches. It follows that the spacing between the end of the cylinder and the end wall of the fountain may be five inches or somewhat less. Since the fountain end wall around the cylinder shaft or gudgeons 19 curves inward toward the cylinder as indicated at 20 (Figure 2), the spacing of the cylinder from the end of the fountain at the point where the cylinder shaft passes through may be only an inch or two, and some of the ink thrown on the cylinder shaft will travel outwardly along it and get into the cylinder bearings. Since ink on the cylinder ends is not scraped off by the doctor, it tends to fly off tangentially of the cylinder, striking the covers 10 and running down inside the fountain. Hence, it is apparent that the condition created in a conventional fountain is such that the cylinder gudgeons 19 may be continuously bathed in ink, which ink tends to creep outwardly into and through the bearing 6 and ultimately into any gears by means of which the cylinder is driven and into any other mechanism, such as axial and circumferential registering mechanism, which may be provided. Furthermore, the lower part of the cylinder, rotating within the well 11, tends to carry ink from the left side (as seen in Figure 2) into the space on the doctor side, and there is a tendency for such ink to pile up and flow back around the ends of the cylinder, thus flooding the cylinder gudgeons 19 with ink, and further aggravating the difficulty.

In accordance with the present invention, a chamber 21 is formed within the fountain and at each end thereof by a partition or ink baffle 25 which as shown in Figure 7, surrounds the lower part of the cylinder. These baffles have arcuately finished ribs with surfaces 26 which are preferably formed on a radius corresponding to the largest cylinder with which the fountain is to be used. This radius may be, in a typical case, seven and a half inches or thereabouts, sufficient clearance being provided between the cylinder and the baffle, so as to eliminate any danger of abrasion of the cylinder surface.

The space outside the baffle 25 and at each end of the fountain, as best shown in Figures 2 and 3, forms the chamber 21, which is provided with an outlet or drain port 27 through which any ink which gets past the baffle is allowed to flow by gravity. The general level of ink maintained within the well and between the baffles 25 will immerse the cylinder sufficiently for printing, but the accumulation of ink on the ends of the cylinder beyond the baffles is prevented. Any ink deflected to the end of the cylinder by the doctor, is thrown off in a generally tangential direction and thus passes over the trunnion 19 rather than toward it. It has been found that in practice, the ink thrown from the end surfaces of the cylinder strikes the inner surface of the arcuate covers 10 and then flows down the walls to the chamber 21 and to the drain port 27, thus keeping the gudgeons free of ink.

Where smaller cylinders than the maximum size shown in Figure 7 are used, adapters 30, shown in Figures 5 and 6, are utilized. These are secured in position as shown in Figures 1, 2, 3 and 4. These adapters, the specific form of which is shown in Figures 5 and 6, are generally semi-annular in form and provided with an external groove 31 which fits over the finished surface 26 of the baffle 25. To each side of the sur-

face 26, the baffle 25 is rabbeted so as to provide a rib fitting within the groove 31. The adapter in turn is formed with a finished cylindrical inner surface 36 corresponding to the surface 26, but being on a lesser radius so as to be spaced from the small diameter cylinder by the required clearance. Each baffle 25 extends clear across the fountain as indicated at 37 and is formed with a pair of threaded bores 38 (Fig. 1) for receiving a pair of bolts or screws 39. A pair of clips 40, held down by the bolts 39, the ends of which engage the upper surface of the baffle 25 and the adapter 30, serve to hold the latter element in position.

What is claimed is:

1. A rotary intaglio ink fountain comprising a generally cylindrical well for holding ink for inking a cylinder and having means including a reciprocating doctor forming an enclosure around the major part of the cylinder and around its shaft, baffles at the ends of the well having cylindrical surfaces adapted to come close to the lower part of the cylinder and extending upwardly above the operating ink level for confining ink within the well, chambers at the ends of the fountain beyond the baffles for receiving leakage, and means for removing leakage ink from the said chambers.
2. A rotary intaglio ink fountain according to claim 1, comprising also arcuate adapter baffles fitting the first said baffles and having cylindrical surfaces concentric with the first said cylindrical surfaces but of smaller radius, for adapting the fountain for use with a correspondingly smaller cylinder.

3. A rotary intaglio ink fountain according to claim 2, in which the adapter baffles are formed with grooves fitting over the first said baffles.

4. In an ink fountain through which ink is circulated and which is arranged to receive a first rotatably supported intaglio printing cylinder of relatively large diameter, and alternatively to receive a second intaglio printing cylinder of smaller diameter, partitions extending between opposite side walls of the fountain and forming a chamber at each end thereof, each said partition extending from the bottom of the fountain upward to within a small clearance distance from the peripheral surface of the said first cylinder when it is in operating position, arcuate adapters each having a convex surface fitted to the upper surface of a partition, and extending to within a small clearance distance from the peripheral surface of the said second cylinder when the second cylinder is in operating position, thereby closing the space between the partition and the cylinder, and an outlet in each chamber for egress of ink passing into the chamber from the fountain.
